TRAFFIC CONTROL APPARATUS

Exra F. Critchlow, Munhall, Pa., assignor to Westinghouse Electric & Manufacturing Company, a corporation of Pennsylvania

Application December 4, 1931, Serial No. 578,891

13 Claims. (Cl. 177—337)

My invention relates to traffic control apparatus and has particular relation to apparatus wherein the display of signals by a right-of-way indicating system provided for a plurality of highways is responsive to the movement of traffic along the highways.

It is an object of my invention to provide for a crossing, a simple traffic control system of the type incorporating street devices that are normally actuated by traffic moving away from the crossing in which the actuation by such traffic of the street devices shall not result in a change in the display of signals by the signalling system.

An additional object of my invention is to provide a traffic control system that is normally to be vehicle-operated but that shall operate on program when a flaw occurs in the operation of the vehicle-responsive triggers.

According to my invention, I provide traffic control apparatus incorporating a right-of-way indicating system to display stop and go signals for a plurality of highways. Normally, go signals are displayed for certain of the highways and stop signals are displayed for certain others of the highways. A regulating device actuatable by a vehicle responsive street device is provided for controlling the period of display of the signals when the signals are changed. The regulating device is normally in such a condition that if, under the proper circumstances, the signals are changed, the go signal is displayed for a predetermined period before the other signals for the highways are displayed.

At times it may happen that the street device is defective in one of its features. In such a case it may not operate in response to vehicle actuation and consequently, the crossing at which the right-of-way indicating system is disposed will freeze with a go signal displayed for the major highway and the stop signal displayed for the minor highway.

I have, therefore, provided a contrivance for automatically checking the efficacy of the street device and for correcting the defective operation thereof.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing in which the single figure is a diagrammatic view showing

a circuit incorporating the principal features of my invention.

The apparatus shown in the drawing comprises a right-of-way indicating system 1 to be disposed at the intersection of a plurality of highways 3 and 5 and to display stop, caution and go signals 7, 9, 11, 13, and 15 for the highways. The crossing at which the system is normally displayed is of the major-minor type and the go signals 13 are normally displayed for the major highway 3 and stop signals 9 for the minor highway 5.

The signalling system 1 is energized through the conducting segments 17, 19, and 21 of a program controller 23 driven from a motor 25 that is normally deenergized. The circuit through which the normal signals 13 and 9 are energized extends from an alternating-current supply bus 27 through conductors 29 and 31, the movable contactor 33 of the program controller 23, the fixed segment 17 of the program controller 23, conductor 35, the go signal 13 for the major highway 3 and the stop signal 9 for the minor highway 5, and conductor 37, to the other alternating current power supply bus 39.

A plurality of street devices 41 are disposed along the minor highway 5. Each street device comprises a photo-sensitive element 43 to be normally energized from a source of radiation 45. The photo-sensitive device 43 is connected between the control electrode 47 and the cathode 49 of an electric discharge device 51 preferably of the grid-controlled type, and an impedance 53 of proper character is connected between the control electrode 47 and the anode 55. Each electric discharge device 51 is supplied with energy from a transformer 57, the primary 59 of which is connected between the alternating current power supply bus lines 27 and 39, and the secondary 61 of which is connected between the cathode 49 and the anode 55 of the electric discharge device 51 through the exciting coil 63 of a relay 65.

When a vehicle moving along the minor highway 5 intersects a beam of radiation whereby a photo-sensitive device 43 is energized, the electric discharge device 51 becomes excited, and the coil 63 of the relay 65 corresponding to the electric discharge device is energized. The upper movable contactor 67 of the relay 65 then engages a plurality of corresponding fixed contacts 69 and a circuit is closed from one alternating current bus line 27 through conductors 71 and 73, the movable contactor 67 of the relay 65 that has been energized, conductors 75 and 77, the excit- 55

ing winding 19 of the program control motor 25, and conductor 81, to the remaining alternating current bus line 38.

The motor 25 is then energized and remains 5 energized at least as long as the beam of light remains interrupted. The movable contactor 33 of the program controller 23 rotates in a counter-clockwise direction in engagement with the segments 17, 18 and 21 and 22 and as it rotates it 10 engages the segment 17 corresponding to the go signal 13 for a predetermined time after which it engages in succession the segment 18 corresponding to the caution signal 11 and the segment 21 corresponding to the stop signal 7 for the major 15 highway 3 and the go signal 15 for the minor highway 5. When the go signal 15 is displayed for the minor highway 5 the vehicle that has heretofore interrupted the beam of radiation to actuate a street device 41 moves across the highway 3 and consequently, ceases to actuate the street device. However, the circuit through the motor 25 is maintained closed by the engagement of a 20 conducting segment 83 with a corresponding movable contactor 85 rotated by the motor 25 through 25 which a circuit extending from one alternating current bus line 21, through conductor 29, the movable contactor 85, the corresponding conducting segment 83, conductors 81 and 89, the coil 18 of the motor 25 and conductor 81 to the remaining alternating current bus line 38.

The program control motor 25 thus continues in its energized condition until the movable contactor 85 through which its circuit has been closed is disengaged from its corresponding conducting segment 83. The motor 25 is normally equipped with a damping device of any well known type which need not be described herein. In the preferred practice of my invention a motor of the watt-hour meter type is utilized and with such 35 a motor the damping device may be simply a magnet cooperating with the disc armature. If a motor of another type is utilized the damping device should be of a corresponding character. The effect of the damping device is to immediately stop the motor when the auxiliary circuit 40 through it is opened.

The segment 83 associated with the auxiliary circuit of the motor 25 is of such character and is so oriented relative to the segments 17, 19, 50 and 21 provided for the display of the signals of the right-of-way indicating device 1 that the movable contactor 33 associated with the right-of-way indicating controller 23 is stopped in engagement with the segment 17 provided for the 55 display of a go signal 13 for the major highway 3, and a stop signal 9 for the minor highway 5. The region of normal engagement of the movable contactor 33 with the segment 17 is preferably near the terminal of the segment at which 60 the period of display of the go signal 13 for the major highway 3 begins, and consequently, any vehicles that actuate the street device 41 associated with the minor highway 5 do not receive a go signal until after at least a predetermined 65 period of display of the go signal 13 for the other highway 3.

Attention is called to the fact that the go signal will only be displayed for the highway 5 if a vehicle stops in a position to intersect the radiant beam from the lamp 45 to the photo-tube 43 for a sufficient interval of time to enable the movable contactor 33 to traverse the whole segment 17. If the vehicle merely passes through the radiant beam without stopping, the relay 65 70 and the motor 25 will not be energized for a

sufficiently long interval of time to produce a change in the signalling system. Hence, vehicles which are moving away from the intersection along lane 5 and do not require a change of signals will not actuate the signalling system. 5

A vehicle moving away from the intersection will intersect the beam of radiations without stopping. If the vehicle moving away from the intersection is one for which the signal has been changed, it will not affect the signalling system at all, for a go signal having been displayed for lane 5, the motor 25 is locked in an energized condition, and it continues to rotate the brush 33, until a stop signal is displayed for the highway, regardless of the influence of vehicles on the 10 beam of radiant energy. On the other hand, if, for example, a go signal is displayed for lane 3 and a vehicle turns from lane 3 into lane 5, it will momentarily obstruct the radiant beam and cause relay 65 and the motor 25 to be momentarily energized. The brush 33 will then advance by a small angle relative to the sector 17, and will then stop. By the slight movement of the brush, the operation of the system is not substantially impaired and the cyclic change of signals will 15 be produced only by such vehicles as require a change of signals and stop at the intersection for a substantial interval of time. Since on the whole, through vehicles will be considerably more frequent than turning vehicles, and since every 20 through vehicle causes the system to be reset in its initial condition with the full time period of the lane 3 go signal available, the operation of the system will be substantially faultless in spite of the slight discrepancies which may be introduced by vehicles turning at the intersection. 25

It is thus seen that a system is provided in which vehicles, such as those which have actuated the vehicle-actuated device and have passed through the intersection, or those which have 30 turned from the main street into the cross street, can move away from the intersection without changing the signal display, even though the vehicle actuated device in the cross street is operated and begins to operate the signal changing mechanism. 45

The checking device comprises a motor 91 which is normally energized and by which a disc 93 incorporating a conducting segment 95 is rotated. The disc 93 may, of course, be geared 50 to the motor and is preferably rotated so slowly that the conducting sector engages corresponding fixed brushes 97 once in long intervals, for example, once every hour, or once every two hours.

When the conducting sector 95 engages the 55 brushes 97, a circuit is closed which extends from a bus line 99 of a direct-current power supply that may be provided by suitably rectifying the alternating current supply, through conductor 101, a brush 97 associated with the checking disc 60 93, the conducting sector 95 of the checking disc 93, a second brush 97, conductor 103, the exciting coil 105 of a relay 107 and conductor 109 to the other direct-current power supply bus 111. When the relay 107 is thus energized its lower movable 65 contactor 113 is disengaged from a plurality of corresponding fixed contactors 115 and the circuit is opened through the sources of radiation 45 whereby the photo-sensitive elements 43 of street devices 41 are energized. 70

It is to be noted that while I have found it convenient to extinguish the sources 45 this procedure is not essential and if it is of any advantage a shutter may usually be thrown into the paths of the beams of light that energize the 75

photo-cells 43 by the actuation of the relay 107. In such a case another relay would of course be necessary to operate the shutter.

Another movable contactor 117 of the checking relay 107 engages a plurality of corresponding fixed contacts 119 and closes a circuit that extends from one direct-current bus line 99 through conductor 121, the exciting coil 123 of another relay 125, conductors 127, 129, and 131, the lower 10 movable contactors 133 of the relays 65 associated with the street devices 41, which have as yet not become energized, conductors 135 and conductor 137, contacts 119 and the movable contactor 117 of the checking relay 107 and conductor 109, to 15 the remaining direct-current bus line 111.

The relay 125 last energized is locked-in by its upper movable contactor 139 which engages corresponding fixed contacts 141 and which closes a circuit through the direct-current power supply 20 and through a push button 143 that may be operated by hand.

If now, in response to the extinguishment of the sources of radiation 45, both relays 65 associated with the street devices 41 become energized, a circuit is closed which extends from one direct-current bus line 99 through conductor 145, a movable contactor 147 and fixed contacts of the relay 125 that has been energized by the excitation of the checking relay 107, a resistor 149 25 of suitable character, the central contactors 151 and associated fixed contacts 157 of the other relays 65 associated with the street devices 41, conductors 153, 131, and 129, the upper movable contactor 139 and fixed contacts 141 of the relay 30 125 that has been energized by the excitation of the checking relay 107 and the movable contactor of the push button 143 to the remaining direct-current bus line 111.

The current whereby the exciting coil 123 of 40 the relay 125 responsive to the checking relay 107 was energized, is thus short-circuited through the resistor 149 and the relay is deenergized. The system is thus reverted to its initial condition 45 since the response to the actuation of the checking device has been proper.

If, on the other hand, one or the other of the street devices 41 should not properly respond to the extinguishment of the corresponding energizing source 45, the corresponding relay 65 would 50 fail to be energized and the lower contactor 133 would remain in engagement with its corresponding fixed contacts 155, the central contactor 151 of the corresponding relay 65 would remain in disengagement from its corresponding fixed 55 contacts 157 and the relay 125 responsive to the actuation of the checking relay 107 would remain energized.

The relay 125 is also equipped with a movable contactor 159 that engages a plurality of corresponding fixed contacts 161 when the relay is energized and closes a circuit extending from an alternating current bus line 27 through conductor 71, the movable contactor 159 and contacts 161 of the relay 125, conductor 89, the 60 windings 79 of the program control motor 25 and conductor 81, to the other alternating current power supply bus 39. The motor 25 is now energized and the program control contactor 33 is rotated providing for the display of stop, caution and go signals 7, 9, 11, 13, and 15 for the highways 3 and 5 in proper succession.

If the flaw in the street device which is defective is of a temporary character only, the system is reverted to its proper major-minor operating condition the next time that the con-

ducting segment 95 of the checking disc 93 engages its corresponding fixed brushes 97. On the other hand, if the defect is of a permanent character, it must be properly remedied by a service man and when so remedied, the system 5 may be reverted to its proper major-minor operation when the service man presses the push button 143 provided for opening the circuit through the coil 123 of locked-in relay 125 associated with the checking system.

My invention has been described above as applied to a particular traffic control system. Specifically, the traffic control system to which it has been applied is of the major-minor type. It will be noted that essentially the outstanding 10 features of my invention should not be limited to such a system and where my invention may be broadened by applications to other systems, I do not wish to be restricted to a traffic control system of the major-minor type. As a matter of fact it will be observed that as regards the checking device incorporated in my improved traffic control system, its essential elements may be widely applied to energy translating apparatus and need not be specifically limited to traffic control apparatus.

As far as the traffic control feature of my invention is concerned, it will be noted that I provide a system devoid of the ordinary time delay relays and particularly applicable to a 30 traffic control system incorporating photo-sensitive street devices. According to my invention a simple system is provided in which the traffic moving away from a crossing does not actuate the street devices.

Although I have shown and described certain specific embodiments of my invention, I am fully aware that many modifications thereof are possible. My invention, therefore, is not to be restricted except insofar as is necessitated by the 40 prior art and by the spirit of the appended claims.

I claim as my invention:

1. A traffic control system comprising a right-of-way indicating device to display sets of stop 45 and go signals for a plurality of highways, means for energizing said signals, a controller incorporating a plurality of cooperative timing elements cooperating with said energizing means to regulate the display of stop and go signals for 50 each of said highways, means for motivating said controller, said motivating means being normally deenergized whereby said controller cooperates with said signals and said energizing means to display go signals for one group of said 55 highways and stop signals for another group of said highways, means to be actuated by vehicles moving along said last named group of highways to coact with said energizing means to energize said motivating means, and, during a 60 predetermined interval of time which is appreciably longer than the interval during which said vehicle-actuable means is actuated by a vehicle in motion along said highway at a normal rate of speed, to maintain said motivating-means 65 energized only so long as said vehicle-actuable means is vehicle-actuated and after said interval of time to maintain said motivating means energized regardless of whether or not said vehicle-actuable means is vehicle actuated, whereby after said interval of time go and stop signals are successively displayed for said last named group of highways and stop and go signals are successively displayed for said first named group of highways and means cooperating with said 70 75

controller and said energizing means to deenergize said motivating means after it has been energized and at the instant that the go signal reappears for said first named group of highways and the stop signal reappears for said last named group of highways.

2. A traffic control system comprising a right-of-way indicating device to display sets of stop and go signals for a plurality of highways, means for energizing said signals, means cooperating with said energizing means to regulate the periodicity of the display and activity of said stop and go signals for said highways, means for motivating said regulating means, said motivating means being normally deenergized whereby said regulating means cooperates with said signals and said energizing means to display go signals for one group of said highways and stop signals for another group of said highways, means to be actuated by vehicles moving along said last-named group of highways to cooperate with said energizing means to energize said motivating means, and during a predetermined interval of time which is appreciably longer than the interval during which said vehicle-actuable means is actuated by a vehicle in motion along said highway at a normal rate of speed, to maintain said motivating means energized only so long as the vehicle-actuable means is vehicle-actuated, and after said interval of time to maintain said motivating means energized independent of said vehicle-actuable means whereby after said interval of time go and stop signals are displayed successively for said last named group of highways and stop and go signals are displayed successively for said first named group of highways and means cooperating with said regulating means and with said energizing means to deenergize said motivating means after it has been energized and at the instant that the go signals reappear for said first named group of highways and the stop signals reappear for said last named group of highways.

3. A traffic control system comprising a right-of-way indicating device to display sets of stop, caution and go signals for a plurality of highways, means for energizing said signals, means cooperating with said energizing means to regulate the periodicity of the display and activity of said stop, caution and go signals for said highways, means for motivating said regulating means, said motivating means being normally deenergized whereby said regulating means cooperates with said signals and said energizing means to display go signals for one group of said highways and stop signals for another group of said highways, means to be actuated by vehicles moving along said last-named group of highways to cooperate with said energizing means to energize said motivating means, and, during a predetermined interval of time which is appreciably longer than the interval during which said vehicle-actuable means is actuated by a vehicle in motion along said highway at a normal rate of speed, to maintain said motivating means energized only so long as said vehicle-actuated means is vehicle-actuated and after said interval of time to maintain said motivating means energized independent of said vehicle-actuable means, whereby after said interval of time, go and stop signals are displayed successively for said last named group of highways and after said interval of time, stop and go signals are displayed successively for said first named group of highways, a signal being displayed before each change

from a stop to a go signal or vice versa, and means cooperating with said regulating means and with said energizing means to deenergize said motivating means after it has been energized and at the instant that the go signal reappears for said first named group of highways and the stop signals reappear for said last named group of highways.

4. A traffic control system comprising a right-of-way indicating device to display sets of stop and go signals for a plurality of highways, means for energizing said signals, means cooperating with said energizing means to regulate the periodicity and activity of the display of said stop and go signals for said highways, means for motivating said regulating means, said motivating means being normally deenergized whereby said regulating means cooperates with said signals and said energizing means to display go signals for one group of said highways and stop signals for another group of said highways, means to be actuated by vehicles moving along said last-named group of highways to cooperate with said energizing means to energize said motivating means, and, during a predetermined interval of time which is appreciably longer than the interval during which said vehicle-actuable means is actuated by a vehicle in motion along said highway at a normal rate of speed, to maintain said motivating means energized only so long as said vehicle-actuable means continues to be vehicle-actuated, whereby after said interval of time go and stop signals are displayed successively for said last named group of highways and stop and go signals are displayed successively for said first named group of highways, additional means cooperating with said energizing means to energize said motivating means when a vehicle, having actuated said vehicle responsive means has ceased to actuate said means and has advanced in response to the display of a go signal for said last named group of highways and means cooperating with said regulating means and with said energizing means to deenergize said motivating means after it has been energized and at the instant that the go signals reappear for said first named group of highways and the stop signals reappear for said last named group of highways.

5. A traffic control system comprising a right-of-way indicating device to display sets of stop and go signals for a plurality of highways, means for energizing said signals, a sectored disc, contacting means cooperating with said disc and with said energizing means to regulate the periodicity and activity of the display of said stop and go signals for said highways, means for motivating said contacting means relative to said disc, said motivating means being normally deenergized whereby said disc and contacting means cooperate with said signals and said energizing means to display go signals for one group of said highways and stop signals for another group of said highways, means to be actuated by vehicles moving along said last-named group of highways to cooperate with said energizing means to energize said motivating means, and, during a predetermined interval of time which is appreciably longer than the interval during which said vehicle-actuable means is actuated by a vehicle in motion along said highway at a normal rate of speed, to maintain said motivating means energized only so long as said vehicle-actuable means is vehicle-actuated and after said interval of time to maintain said motivating means energized independent of said vehicle-actuable means,

whereby, after said interval of time, go and stop signals are displayed successively for said last-named group of highways and stop and go signals are displayed successively for said first named 5 group of highways, a second sectored disc and contacting means cooperating with said second disc and with said energizing means to deenergize said motivating means after it has been energized and at the instant that the go signals 10 reappear for said first-named group of highways and the stop signals reappear for said last-named group of highways, said last-named contacting means being motivated relative to said last-named disc by the motivating means for said 15 first-named contacting means relative to said first-named disc.

6. In translating apparatus of a type incorporating a trigger element, including a photo-sensitive device and means for exciting said photo-sensitive device, an operative system and means to respond to an actuation of said trigger element to actuate said operative system to perform its 20 operation, means for periodically deenergizing said exciting means to actuate said trigger element to test the efficacy of said trigger and said trigger-responsive means and means to respond to the inefficacy of said trigger or said trigger-responsive means to actuate said operative system to sufficiently perform the operations of said 25 translating apparatus to render it useful for the purpose for which it is intended.

7. In combination with a photo-sensitive device, a source of radiations for normally exciting said photo-sensitive device, an operative system 30 and means responsive to a decrease in the radiation impinging on said photo-sensitive device to actuate said operative system to perform its operation, of means for periodically deenergizing said source of radiation to test the efficacy of 35 said photo-sensitive device and said means responsive thereto and means to respond to the inefficacy of said photo-sensitive device or said means responsive thereto to actuate said operative system to sufficiently perform its operations 40 and to render it in this condition useful for the purpose for which it is intended.

8. In combination with a photo-sensitive device, means for exciting said photo-sensitive device, an operative system and means responsive to 45 a change in the state of excitation of said photo-sensitive device to actuate said operative system to perform its operation, of means for changing the state of excitation of said photo-sensitive device to test the efficacy of said photo-sensitive 50 device and said means responsive thereto and means to respond to the inefficacy of said photo-sensitive device or said means responsive thereto to actuate said operative system to sufficiently perform its operations to render it useful for the 55 purpose for which it is intended.

9. A traffic control system comprising right-of-way indicating means to display stop and go signals for a plurality of highways, means for energizing said indicating means, means cooperating 60 with said energizing means and said indicating means for regulating the display of said stop and go signals for said highways, means to be vehicle actuated for controlling the activity of said regulating means, means for periodically actuating 65 said vehicle-actuable means artificially in the same manner as it would be actuated by vehicles to test the efficacy thereof, said means to respond to the inefficacy of said vehicle actuable means to actuate said regulating means to produce a se- 70

quential display of stop and go signals for said highways.

10. A traffic control system comprising right-of-way indicating means to display stop and go signals for a plurality of highways, means for 5 energizing said indicating means, means cooperating with said energizing means and said indicating means for regulating the display of said stop and go signals for said highways, means associated with certain of said highways and comprising a photo-sensitive device and means for exciting said photo-sensitive device, said exciting means to be rendered inactive by vehicles moving along said highways for controlling the activity 10 of said regulating means, means for periodically rendering said exciting means inactive artificially in the same manner as it is rendered inactive by vehicles to test the efficacy of said controlling means and means to respond to the inefficacy of 15 said controlling means to actuate said regulating means to produce a sequential display of stop and go signals for said highways.

11. A traffic control system comprising a right-of-way indicating device to display sets of stop and go signals for a plurality of highways, means 20 for energizing said signals, means cooperating with said energizing means to regulate the periodicity of the display and activity of said stop and go signals for said highways, means for motivating said regulating means, said motivating means 25 being normally deenergized whereby said regulating means cooperates with said signals and said energizing means to display go signals for one group of said highways and stop signals for another group of said highway, means to be actuated by vehicles moving along said last-named group of highways to cooperate with said energizing means to energize said motivating means, and, during a predetermined interval of time which is appreciably longer than the interval during 30 which said vehicle-actuable means is actuated by a vehicle in motion along said highway at a normal rate of speed, to maintain said motivating means energized only so long as said vehicle-actuable means continues to be vehicle-actuated, whereby after said interval of time go and 35 stop signals are displayed successively for said last named group of highways and stop and go signals are displayed successively for said first named group of highways and means cooperating with said regulating means and with said energizing means to deenergize said motivating means, after it has been energized, and to leave it in such a condition that the go signal is displayed for said first-named group of highways, and, when 40 said motivating means is energized by a subsequent actuation of said vehicle-responsive means said go signal will continue to be displayed at least for a predetermined period of time.

12. A traffic control system comprising a right-of-way indicating device to display stop and go signals for a plurality of highways, a stop signal being normally displayed for one of said highways, means for varying the display of said signals, means to be actuated by traffic moving on said 45 last-named highway for energizing said varying means to limit the display of said stop signal to a predetermined interval of time and to follow it by the display of a go signal for said last-named highway, said varying means being energized only 50 while vehicles actuate said vehicle-actuable means during the predetermined interval of time to which the display of said stop signal is limited after actuation of said vehicle-actuable means, and means for energizing said varying means, 55

independent of said vehicle responsive means as long as a go signal is displayed for said highway.

13. A traffic control system comprising a right-of-way indicating device to display sets of stop and go signals for a plurality of highways, means for energizing said signals, a sectored disc, contacting means cooperating with said disc and with said energizing means to regulate the periodicity and activity of the display of said stop and go signals for said highways, means for motivating said contacting means relative to said disc, said motivating means being normally deenergized whereby said disc and contacting means cooperate with said signals and said energizing means to display go signals for one group of said highways and stop signals for another group of said highways, means to be actuated by vehicles moving along said last-named group of highways to cooperate with said energizing means to energize said motivating means, and, during a predetermined

interval of time which is appreciably longer than the interval during which said vehicle-actuable means is actuated by a vehicle in motion along said highway at a normal rate of speed, to maintain said motivating means energized only so long as said vehicle-actuable means is vehicle-actuated and after said interval of time to maintain said motivating means energized independent of said vehicle-actuable means, whereby, after said interval of time, go and stop signals are displayed successively for said last-named group of highways and stop and go signals are displayed successively for said first-named group of highways, and means cooperating with said motivating means to deenergize said motivating means after it has been energized and at the instant that the go signals reappear for said first-named group of highways and stop signals reappear for said last-named group of highways. 5

EZRA F. CRITCHLOW. 20
